Claims priority, application Great Britain, Oct. 11, 1962, 38,468/62

2 Claims. (Cl. 103—126)

This invention relates to gear pumps of the kind in which side plates, loaded by the action of pump-delivery pressure, are employed to increase the volumetric efficiency of the pump and has for an object to provide an improved gear pump of the kind specified adapted to maintain high volumetric efficiency for a relatively long time. This makes the invention particularly valuable for pumps intended to deliver liquid of low viscosity and/or poor lubricating qualities, especially where the liquid is to be delivered against considerable pressure.

In operation of a gear pump the part of the circumference of each gear which travels from the suction side to the delivery side of the pump is subjected to a hydrostatic pressure which rises gradually as each tooth gap approaches the delivery side, and this phenomenon in conjunction with the inherent difference of pressure between the inlet chamber and the delivery chamber of the pump results in a tendency of the gears, as a result of play in the bearings and resilient deflection of the gear shafts, to make metallic contact with the housing at the low-pressure side of the housing. Herein the delivery chamber is the chamber accommodating that part of each gear which travels on the delivery side from the point of sealing contact with the housing to the point of intermesh and the inlet chamber is the chamber accommodating that part of each gear which travels on the inlet side from the point of intermesh to the point at which the tooth gaps become sealed by contact with the housing. In practice this tendency is utilised in pumps of the kind specified to cause, during so-called running-in of the gear pumps, due to initial wear, the housing surfaces at the low pressure side to become very intimately conform with the co-operating gear surface with resultant excellent sealing qualities at the end of the running-in period. In pumps delivering liquids of good lubricating qualities this excellent sealing contact will be maintained for a long time, but difficulties arise in pumps employed for delivering liquids of poor lubricating qualities such as wide-out gasoline, in which wear of the internal parts of the pump is liable to a major limitation in the operating life of the pump.

According to the present invention the life of the pump can be considerably extended if the pump housing is made symmetrical in such manner that when one side of the pump housing has become worn so as to unduly affect the seal between the pump housing and the tips of the gear teeth, the pump can be dismantled and reassembled with the housing turned by 180° so as to interchange the inlet and outlet sides of the housing body. The above-mentioned unbalance of pressure will then cause the gears to make contact with the wall of the gear housing at the side which previously was the high-pressure side, and after a new running-in period the original quality of seal will be substantially restored. In order to permit this reversal, the housing must be symmetrical in relation to two mutually perpendicular planes of symmetry one of which is preferably the plane containing the axes of the two gears. If the housing is symmetrical in relation both to that plane and to a plane perpendicular to the said plane and parallel to the gear axes, the result can be achieved alternatively either by turning the housing in its own plane or by turning it about

2

an axis perpendicular to the last-mentioned plane of symmetry. Thus the invention may be broadly stated to be characterised by the fact that the housing body is symmetrical about at least two of three mutually perpendicular planes of which one contains the axes of the said gears and another is parallel to the said axes, so that the gears can be assembled with the housing body in at least two alternative positions in which the housing is turned relative to the gears about the line of intersection of two planes of symmetry.

Wear is also liable to occur at the tooth flanks, however, and in order to reduce this wear, or at least to distribute it more uniformly so as to delay the increase in leakage through the zone of intermesh, the pump is preferably, according to another feature of the invention, equipped with intermeshing pumping gears having numbers of teeth which are prime relative to each other, the number of teeth differing, for example, by a single tooth. It will be appreciated that this construction will make it impossible to preserve the last-mentioned symmetry but, as already stated, the reversibility feature can still be employed by turning the pump body in the second one of the two methods above referred to.

The invention is preferably employed in combination with other features which contribute to high volumetric efficiency of the pump, more particularly in combination with the use of pressure-loaded side plates which are applied to the side surfaces of the gears by the delivery pressure of the pump, and in which substantial alignment of the pressure forces acting on the two sides of each side plate is achieved by means of a sealing ring or gasket which separates a zone in which pump delivery pressure acts from a second zone under pump inlet pressure. This ring or gasket is accommodated in a surface groove of the side plate, but in order to separate those zones, the sealing ring or gasket must pass across the peripheral edge of the side plate or plates into contact with the side surface of the housing so that one of the inlet and outlet chambers of the pump is inside the area encircled by the sealing ring and the other outside. According to the invention to permit the pump body to be reversed in the manner stated without abandoning this sealing ring feature, two grooves adapted to accommodate the portion of the sealing ring between the two points at which it crosses the edge of the, or each side plate are formed in the housing body at the two positions respectively required for assembly before and after reversal of the pump housing body.

In order that the invention may be more readily understood, an embodiment will now be described with reference to the accompanying drawings, in which

FIGURE 1 is an axial section of the gear pump according to the invention,

FIGURE 2 is a section on line 2—2 of FIGURE 1,

FIGURE 3 is an end view of the housing body with one of the end plates and sealing gaskets, and

FIGURE 4 is a cross-section on line 4—4 of FIGURE 3, showing the pump with the housing end plates removed.

Referring now to the drawings, the pump comprises a housing body 1 which contains the usual gear chamber 2 constituted by two inter-penetrating parallel cylindrical bores 3 and 4 which respectively accommodate the intermeshing pumping gears 5 and 6, while flattened portions 7 and 8 in the zone of intersection of the gears form respectively an inlet chamber and an outlet chamber. A pump inlet bore 14 and a pump outlet bore 15 are arranged in the central plane of the pump body 1 and symmetrically to the plane containing the axes of the two bores 3 and 4. The diameter of bore 4 and gear 6 is ten percent greater than that of bore 3 and

gear 5, the gear 5 having ten teeth, while gear 6 has eleven teeth of the same pitch, so that each tooth of the gear 5 will, after each rotation of the gear, instead of entering the same tooth gap of gear 6, enter the next preceding tooth gap thus ensuring uniform distribution of wear between the individual teeth. The gears are supported in housing end members 9 and 10, and the end member 9 also contains the bearings for a drive shaft 11 which is coupled to the gear 5 to transmit power to the pump. The two end members 9 and 10 are secured to the housing body 1 by bolts 12 and are located in relation to it by dowels 13; the bolts 12 and the dowels 13 are arranged symmetrically to the plane containing the axes of the two gears. The axial length of the gears 5 and 6 is less than that of the housing body 1, and the gear cavity 2 contains, in addition to the pumping gears, and at each side of the latter, a pair of side plates 16 and 17. The outer face of each of these plates is provided with a surface groove 18 which leads from a point at the edge of the plate, in a curved line encircling the journals 5a and 6a of the two pumping gears 5 and 6, to a second point at the edge of the plate 16 or 17. This groove is continued by a groove 19 in the housing body 1 so as to form jointly with the latter a closed path. A round-section endless sealing gasket 20 is accommodated in the combined groove 18, 19 and co-operate with the opposed surface of the housing end body 9 or 10 to isolate the zone on the surface of the side plate which includes the outer ends of the bores through which the gear journals extend, and which communicates through a bevelled portion 21 of the side plate with the pump inlet 15, from the remainder of the outer surface of the pump side plate, which through a second bevel 22 communicates with the pump outlet 14.

In addition to the groove 19 and symmetrically to the latter in relation to the plane containing the axes of the two pumping gears, the housing body contains a second identically dimensioned groove 19a, which in the illustrated position of the pump is not utilised.

When, after prolonged use, the surfaces of the bores adjacent to the inlet 15, towards which the gears are urged by the hydrostatic pressure, have been worn to such an extent as to unduly impair the volumetric efficiency can be restored to approximately its original value by dismantling the pump and reversing the housing body 1 about a line which extends perpendicularly to the two gear axes in the common plane of the latter so that the surface previously co-operating with housing end body 9 will now co-operate with housing end body 10 and vice versa. It will be observed that as a result of this reversal the grooves 19a of the housing will now lie at that side of the pump axis which contains the pump inlet and to which the gasket 20 extends, so that now the grooves 19a from the continuations of the grooves 18 and accommodate part of the gasket 20, while the grooves 19 are unused. When the pump is now operated, the pressure at the pump outlet, now constituted by the bore 15, will urge the gears into contact with the portions of the bores 10 and 11 adjacent to the bore 14, which now constitutes the pump inlet, that is to say with portions of the bores 10 and 11 which up to then have not been worn, so that after a fresh running-in period substantially the original volumetric efficiency of the pump is restored and the pump is given another spell of life substantially equal to its original one.

While one embodiment of the pump according to the invention has been described in some detail with reference to the drawings, it will be appreciated that the use of the invention is not restricted to this particular form of pump. Thus the number of gear teeth of the two pumping gears may be made different without losing the beneficial effect on the life of the gears; in this case the numbers of the teeth of two gears should be relatively prime. Furthermore, while the sealing ring or gasket 20 is illustrated as encircling the gear journals and a connec-

tion with the pump-inlet port, the pump may alternatively be provided with a gasket which encircles an area not containing either of the two journals and which is connected to the pump outlet instead of the pump inlet. The invention may be applied equally to gear-type motors as to gear pumps in the narrower sense, subject to modifications which are obvious to those skilled in the art, for example to the effect that the chamber inside a gasket encircling the two gear journals would in that case communicate with the motor outlet, instead of the pump inlet, since in that case this is the low-pressure port.

Finally it will be evident to those skilled in the art that the use of two pumping gears having relatively prime numbers of teeth may be employed independently of the use of a symmetrical pump housing and vice versa if desired.

What I claim is:

1. A gear pump comprising two intermeshing pumping gears each having at least one journal, and a housing body having a cavity in which the gears are rotatable about parallel axes, and having bores extending from said cavity coaxially with the journals of each gear, wherein the housing body comprises at least two parts joined in a plane extending through said cavity, said parts being provided with locating means for determining their accurate relative position, said cavity and locating means being symmetrical about at least two of three mutually perpendicular planes of which one contains the axes of said gears, another is parallel to the said axes, and the third is perpendicular to the said axes, so that the gears can be assembled with the housing body in at least two alternative positions, in which the housing is turned relative to the gears about the line of intersection of two planes of symmetry, and wherein the pump further comprises a pressure-loaded side plate having two parallel plane surfaces one of which is applied to a side surface of the gears by the delivery pressure of the pump, and in which substantial alignment of the pressure forces acting on the two sides of the side plate is achieved by means of a sealing ring or gasket which separates a zone in which pump-delivery pressure acts, from a second zone under pump-inlet pressure, part of the length of said ring being accommodated in a groove formed in the other plane surface of the said side plate and interconnecting two points at the circumference of said side plate and two grooves, adapted to respectively accommodate the remainder of the sealing ring, being formed in the housing body to respectively interconnect the points of the housing body located opposite to said two points at the circumference of the side plate before and after reversal of the pump housing body relative to the gears.
2. A gear pump as claimed in claim 1, wherein the intermeshing pumping gears have numbers of teeth which are prime relative to each other, the housing body being so constructed as to enable it to be assembled with the gears in two alternative positions obtained by turning the housing body relative to the gears about an axis perpendicular to and intersecting the axes of the journals of both gears.
